UNITED STATES PATENT OFFICE.

MICHAEL J. GREEN, OF ROCKFORD, ILLINOIS, ASSIGNOR TO ECLIPSE GAS STOVE COMPANY, OF ROCKFORD, ILLINOIS, A CORPORATION OF ILLINOIS.

WALL-BURNER.

1,252,687.

Specification of Letters Patent. Patented Jan. 8, 1918.

Application filed June 5, 1915. Serial No. 32,423.

To all whom it may concern:

Be it known that I, MICHAEL J. GREEN, a citizen of the United States, residing at Rockford, in the county of Winnebago and 5 State of Illinois, have invented certain new and useful Improvements in Wall-Burners, of which the following is a specification.

There are many occasions when an individual burner heating means of small capacity 10 is desirable. Such a means is found to be especially useful and necessary in a doctor's or dentist's office, in laboratories, bathrooms, etc., where it is often desired to heat a small quantity of water, to prepare medicines, to 15 cook or to heat any article or receptacle of comparatively small size. To meet this need in a most simple and efficient manner has been the primary object of my invention, and I have, therefore, provided a wall 20 burner of novel construction adapted to be secured to any wall or like support in such manner as to be conveniently accessible.

Another object of my invention is to provide as an article of manufacture a wall 25 burner of a simple and pleasing design, practical in operation, and which can be manufactured at a low cost.

More specifically, further objects of my invention are to provide a wall burner comprising in general a wall plate adapted to be secured to a wall, a bowl connected to the wall plate at the face thereof, a grate mounted on the bowl, and a burner disposed within the bowl below the grate for heating 30 an article mounted thereupon; to provide means for deflecting rising heated air outwardly from a wall to which the wall plate may be secured; to embody said deflecting means in the wall plate structure; to enhance the appearance of the wall burner and to give a permanent finish by coating its 35 deflecting face with a porcelain enamel, or a like infusible substance one that will not deteriorate or become tarnished from the presence of heat; and to insulate the wall 40 burner from the wall to which it is secured so that the wall plate in becoming heated will not mar or damage the wall.

Other objects and attendant advantages of 45 the invention will be apparent as the same becomes better understood by reference to

the following detailed description, when considered in connection with the accompanying drawings, wherein—

Figure 1 is a face view of a wall burner 55 embodying my improvements;

Fig. 2 is a plan view of the wall burner;

Fig. 3 is a vertical sectional view through the wall burner taken on the line 3—3 of Fig. 1; and

Fig. 4 is a fragmentary view partly in vertical section through a portion of the bowl, illustrating the manner in which the same is attached to the wall plate.

Referring to the drawings, it will be observed that the wall burner comprises in general a wall plate designated in general by reference character 5 adapted to be secured in upright position to a wall, and means disposed at the face of and connected 60 to the wall plate for supporting and heating an article, which means will be more fully described hereinafter. The wall plate may be of any suitable configuration, a preferred shape being rectangular, as shown 65 in Fig. 1. The wall plate, preferably formed as an imperforate casting, provides a substantial support for the article supporting and heating means and serves to shield the wall in proximity to the wall burner from 70 being damaged from heat incident to the use thereof. By providing the wall plate on its rear face with laterally projecting feet 6, the wall plate may be held, when secured to a wall by suitable means such as 75 screws 7, in spaced relation to the wall, whereby the wall plate is insulated therefrom by the air space thus formed. However, if desirable, other means may be employed to insulate the wall plate from the 80 wall. To further provide against blemishing or marring the wall in proximity to the wall burner, I have shaped the upper portion of the wall plate to form a deflector 8, having a concave or incurved face adapted 85 to deflect rising heated air outwardly away from the wall. Since the wall burner of the character to which my invention relates is used particularly as an interior article, it is desirable that it be finished so as to be 90 pleasing to the eye and that the finish be of a permanent nature. With this end in view

and also the purpose of economy in manufacture, I have formed the wall plate of two sections, viz., a lower body section 9 and an upper deflector section 11 articulated 5 in a suitable manner as at 12 and held fixedly together by means of bolts 13, which serve also to connect the bowl to the wall plate as will be described hereinafter. The face of the deflector 11 is finished by applying 10 thereto some suitable infusible coating, preferably that of porcelain enamel, the qualities of which will not be affected by heat from the heating means. The lower body section 9 may be finished in any suitable manner, it 15 being preferred to nickel the marginal portions thereof, since this finish is less expensive than that applied to the top section; but will deteriorate if applied to the deflector and subjected to extreme heat.

20 The means for supporting the burner and an article to be heated thereby, comprises in general a bowl 14 of inverted frusto-conical shape, provided about its upper portion with a horizontal web 15 having a depending flange 16, the back portion of the web abutting against a face of the wall plate section 9 and being provided with a pair of depending bifurcated lugs 17. By reason of the lower ends of the said lugs 17 resting 25 against abutments 18 projecting from the face of the wall plate section 9 and the edge of the web 15 abutting against said wall plate section and resting on lugs 18' also projecting from the face of the wall plate section 9, bolts 13 disposed intermediate said 30 points of abutment and engaging the lugs 17, as shown, may be drawn tight and thereby hold the bowl and both sections of the back wall in fixed relation. A grate or grid 35 19 of suitable construction rests on an annular seat 21 formed in the top portion of the bowl, the grate serving as the direct support upon which an article is mounted to be heated. Upstanding lugs 22 prevent the 40 grate from being displaced.

The bowl 14 serves as a housing to a heating means disposed below the grate 19 and also aids in securing efficient operation of the heating means. The heating means comprises a gas burner 23 fixedly connected to the 45 upper end of a gas supply pipe 24. The pipe 24 passing through an aperture in a bridge piece 25, which is integral with the bowl and spans an air intake opening 26 formed in the base thereof, is fixedly connected to the bridge piece by a nut 27 threaded on the pipe and in engagement with the underside of the bridge piece drawing the base of the burner into engagement with the top of said 50 bridge piece. The gas burner is thus fixedly mounted in the base of the bowl whereby to direct a proper flame upwardly to heat an article positioned on the grate 19, the efficiency of the burner being enhanced by in-

take of air through the circumferential passage 26.

It will be obvious that to operate the wall burner, a suitable gas pipe or hose (not shown) leading from a gas supply may be connected to the lower end of the gas pipe 70 and provided with a suitable valve for controlling the supply of gas to the burner. The lower portion of the gas pipe is braced by a bracket designated in general by reference character 28, fixedly secured to the face 75 of the wall plate. This bracket is shaped to provide a match receptacle and also a cigar holder as is indicated at 29.

From the foregoing, it will be apparent that the wall burner may be easily secured 80 to a wall wherever convenient and insulated therefrom so as to prevent marring of the wall through conduction of heat from the wall plate; that any of various articles or receptacles may be positioned on the grate 85 and very economically heated by the gas burning means; that the bowl serves as a means for confining the flame of the burner to its heating operation so that the garments of those in proximity to the burner will not 90 be damaged, and serves also as a means for supporting the grate and the gas burner in their proper relation; that the heated air rising from the burner at the wall side thereof during operation will be deflected by 95 reason of the peculiar construction of the wall plate, outwardly away from the wall so that the same will not be blemished thereby; and that by reason of the sectional structure of the wall plate and the particular finish 100 given to the deflector portion thereof, a structure is resultant which may be economically manufactured and which will retain its finish when subjected to the presence of extreme heat.

While I have described and illustrated one practical embodiment of my invention, it should be understood that I do not limit myself to the details of structure shown, since the same may be variously changed 110 without departing from the spirit and scope of the invention as set forth in the appended claims:

I claim:

1. As an article of manufacture, a wall burner comprising a wall plate having a lower supporting portion and an upper deflecting portion, a bowl member secured to the wall plate below the deflecting portion, a grid carried by the upper part of said bowl member for receiving articles to be heated, said bowl member having an air inlet formed in the lower part thereof, a burner extending through said inlet into the bowl member, and means for maintaining the burner in heating position within the bowl member below the grid.
2. As an article of manufacture, a wall

burner comprising a wall plate, having its upper portion formed to constitute a deflector, a bowl member secured to said wall

for maintaining the burner in the bowl member in heating position beneath the article support.

plate below the deflecting portion, a support
